US00D785775S

(12) **United States Design Patent** (10) **Patent No.:** **US D785,775 S**
(45) **Date of Patent:** **** May 2, 2017**

(54) **COVER FOR AN AIR FILTRATION DEVICE**

(71) Applicant: **Illinois Tool Works Inc.**, Glenview, IL (US)

(72) Inventors: **Stephen J. McPhiliamy**, Chicago, IL (US); **Antonio J. Belton**, Richton Park, IL (US); **John S. White, Jr.**, Chicago, IL (US)

(73) Assignee: **Illinois Tool Works Inc.**, Glenview, IL (US)

(**) Term: **15 Years**

(21) Appl. No.: **29/558,426**

(22) Filed: **Mar. 17, 2016**

Related U.S. Application Data

(63) Continuation of application No. 29/496,382, filed on Jul. 11, 2014, now Pat. No. Des. 752,728, which is a continuation of application No. 29/449,570, filed on Mar. 15, 2013, now Pat. No. Des. 732,647.

(51) **LOC (10) Cl.** **23-04**

(57) **CLAIM**

The ornamental design for a cover for an air filtration device, as shown and described herein.

DESCRIPTION

FIG. 1 is a top perspective view of a cover for an air filtration device of our new design.

FIG. 2 is a front elevation view thereof;

FIG. 3 is a right side elevation view thereof;

FIG. 4 is a rear elevation view thereof;

FIG. 5 is a left side elevation view thereof;

FIG. 6 is a top plan view thereof; and,

FIG. 7 is a bottom plan view thereof.

The broken lines are included for environmental purposes only and form no part of the claimed design.

1 Claim, 7 Drawing Sheets
